DESIGN FOR A BASEBOARD REGISTER

Carl S. Lundgren, Muskegon, Mich., assignor to
Air Control Products, Inc., Muskegon, Mich., a
corporation

Application November 13, 1939, Serial No. 88,240

Term of patent 7 years

To all whom it may concern:

Be it known that I, Carl S. Lundgren, a citizen
of the United States, residing at Muskegon, in
the county of Muskegon and State of Michigan,
have invented a new, original, and ornamental
Design for a Baseboard Register, of which the
following is a specification, reference being had
to the accompanying drawing, forming part
thereof.

In the drawing,

Figure 1 is a front elevational view of a base-
board register showing my new design;

Figure 2 is a side elevational view thereof; and
Figure 3 is a top plan view thereof.

I claim:

The ornamental design for a baseboard register,
as shown.

CARL S. LUNDGREN.
